ABSORPTION REFRIGERATION

Wilhelm Georg Kögel, Stockholm, Sweden, assignor to Aktiebolaget Electrolux, Stockholm, Sweden, a corporation of Sweden

Application June 7, 1945, Serial No. 598,125
In Sweden June 10, 1944

3 Claims. (Cl. 62—119.5)

1

This invention relates to absorption refrigerating apparatus employing a thermosiphon pump, and has for its object to provide an improvement to eliminate the danger of the pump pipe becoming clogged which sometimes occurs in hermetically closed absorption refrigerating apparatus including apparatus of the type containing a corrosion protective substance, such as an alkali chromate, for example, dissolved in the absorption solution.

It is already known to provide a liquid circulating pump for absorption refrigerating apparatus in the form of a pipe having a small internal diameter, so that vapor formed in such pipe due to heating will produce a thermosiphon effect and thereby effect circulation of absorption solution between an absorber and boiler of the apparatus. In order to obtain sufficient pumping action, a relatively small length of the pump-pipe is generally heat-conductively connected to the heat-absorbing element of the apparatus, usually a flue. The intense heating of the narrow pipe greatly increases the danger of the narrow passage therein becoming clogged by precipitation of solid matter when overheating of the pump-pipe should occur, in view of the fact that it contains only a very small quantity of liquid.

On the other hand, it is known to employ, in place of a heat-operated part of a pump-pipe, an unheated dome into which the riser pipe of the pump depends with its lower open end extending downwardly into the liquid within the dome. By producing a small excess of pressure in the vapor space of the dome, slugs of liquid are repeatedly segregated by the vapor and pass upwardly through the pipe by vapor lift action. Such so-called bell-pumps are, however, not suitable in every type of absorption refrigerating apparatus and in certain cases operate less satisfactorily than thermosiphon-pumps of the type first mentioned.

In accordance with the present invention, an improvement is provided in which all of the advantages associated with bell-pumps are obtained while the disadvantages of such pumps are substantially eliminated. This is accomplished by providing a pump in which at least the lower part of the pump-pipe is heat-conductively attached to the heat-absorbing element of the refrigerating apparatus along a common generatrix, and in which such lower part is of greater internal diameter than the riser pipe of the pump. While the operation of the pump of the invention is not fully understood, it is believed that a mixture of vapor and liquid is formed in the larger lower

2

heated part of the pump pipe and such liquid, due to the thermosiphon effect, passes upwardly through the pump-pipe and thereby effects circulation of liquid between the absorber of the apparatus and its boiler.

The invention, together with the objects and advantages thereof, will be more fully understood from the following description and accompanying drawing illustrating different arrangements for practicing the invention, and in which

Fig. 1 more or less diagrammatically illustrates an absorption liquid circuit of absorption refrigerating apparatus including a generator embodying the invention which is shown in section.

Fig. 2 is a view in elevation of a form of generator which is different from that of Fig. 1 and to which the invention has been applied;

Fig. 3 is a fragmentary sectional view of the bottom part of a generator like that shown in Fig. 1 illustrating another modification of the invention; and

Fig. 4 is a fragmentary view, partly in section, of a generator generally like that shown in Fig. 2 illustrating details of a further modification.

10 In Fig. 1, 10 designates a heat-absorbing element, for example, a heating tube or flue of a generator unit of an absorption refrigerating apparatus of the inert gas type adapted to be heated by a suitable heat-source, such as a fluid fuel burner 6, for example. The lower part of an upright boiler pipe 11 is heat-conductively connected to the flue 10 along a common generatrix. The upper part or extension 12 of the pipe 11 is connected to the condenser of the apparatus, not shown.

To the lower part of the boiler pipe 11 is connected a liquid circulating pump 14 and 16 of the apparatus for lifting absorption solution to the higher level in a stand-pipe 13. The heat-absorbing part 14 of the pump is formed of piping having a relatively large internal diameter, and preferably from one and one-half to two times the diameter of the riser pipe 16, so that free relative movement of vapor and liquid can take place in such heat-absorbing part, for example. The lower end of the pipe section 14 is connected by a short conduit 15 to the boiler 11, while the upper end thereof is connected to the riser pipe 16 of the pump which has an internal diameter of such size that liquid will be raised therethrough by "thermosiphon effect."

The riser pipe 16 communicates with the stand-pipe 13. In certain instances it may be desirable to thermally separate to a certain extent the narrow pipes 15 and 16 from the flue 10, whereby

heat will be supplied to the pump principally by heat transfer from the flue to the larger pipe section 14. The solution pumped into the stand-pipe 13 slowly streams downwardly through the outer passage of a liquid heat exchanger 17 of the apparatus which is in the form of a coil disposed about the generator or boiler unit 10, 11, 14 and 16. After flowing through the outer passage of the liquid heat exchanger, solution weak in refrigerant passes through a conduit 18 to the absorber 7 of the apparatus. In a well known manner inert gas rich in refrigerant enters an absorber vessel 21 through a conduit 8 and inert gas weak in refrigerant passes from the upper end of absorber 7 through a conduit 9.

The boiler 11 is supplied with absorption solution rich in refrigerant from the inner passage of the heat exchanger which is formed of piping and connected at its upper end at 19 to boiler pipe 11, such connecting point being located at a level with or above the highest point of the liquid heat exchanger. A conduit 20 connects the opposite end of the inner passage of the liquid exchanger to an absorber vessel 21 of the apparatus, partly shown. The boiler unit and the heat exchanger are embedded in a body of heat-insulation 22.

Fig. 3 illustrates another embodiment of the invention which is generally like Fig. 1 and differs therefrom in that the pump-chamber 14 is formed of one leg of the boiler pipe 11 whose lower end is bent into U-form. In this way the narrow passage provided by the conduit 15 (Fig. 1), as well as the welded joint between such conduit and the pump chamber 14, respectively, are avoided.

In Fig. 2 the invention is embodied in a type of generator unit in which the chamber of the boiler is formed by the flue 10 and a tubular member 25 which is concentrically disposed about and spaced from the flue. The chamber of the boiler communicates through a conduit 26 with the condenser of the apparatus, not shown. From the boiler solution weak in refrigerant passes through a conduit 27 and the outer passage of the liquid heat exchanger 17 to the absorber. In this embodiment the liquid heat exchanger 17 is arranged outside the heat insulation of the generator unit, not shown, and in a well known manner may be embedded in a body of insulating material. The internal pipe 19 of the liquid heat exchanger is connected to a pipe 28 which is welded to the flue 10 and forms the pump chamber. The upper end of the pipe 28 is connected to the riser-pipe 29 of the pump. This latter pipe 29 is connected to the upper part of the tubular member 25 of the boiler.

It has proved particularly advantageous when constructing thermosiphon pumps of the invention to reduce as much as possible the number of welded joints in the pump or parts immediately associated therewith. Such welded joints, in individual instances, sometimes tend to contribute to clogging taking place in the narrow pump passage. The embodiment of Fig. 3 illustrates one manner of reducing the number of welded joints at the pump, and Fig. 4 shows another manner of accomplishing this result.

In the embodiment of Fig. 4, in which the reference numerals correspond to those in Fig. 2, the liquid heat exchanger is formed and connected to the boiler and the absorber vessel, respectively, so that the solution weak in refrigerant flows from the boiler 25 through the internal pipe 19 thereof to the absorber, while the external pipe

thereof leads rich solution from the absorber vessel directly to the riser pipe 29 of the thermosiphon-pump.

The outer tubular member or piping 30 of the liquid heat exchanger is bent upwardly at one end, such bent portion 31 being welded to the flue 10 along a common generatrix, that is, on a line substantially parallel to the longitudinal axis of the flue. The upwardly bent end portion 31 of the outer piping of the exchanger forms the chamber of the pump. Through the opening at the top of this chamber extend the internal pipe 19 of the liquid heat exchanger as well as the riser pipe 29, the upper edge of the pipe portion 31 being flattened and welded about both the pipes 29 and 19. This arrangement for flowing the rich solution directly to the riser pipe of the pump through the outer jacket or pipe of the liquid heat exchanger, and for flowing weak solution from the boiler through the internal pipe of the liquid heat exchanger may, of course, also be applied to boilers like those shown in Figs. 1 and 3, for example.

In view of the foregoing, it will now be understood that the invention is not limited to the embodiments diagrammatically shown but may be varied in several ways within the scope of the basic spirit of the invention. The chamber of the pump may thus be formed in different ways, as will be evident from comparing the different embodiments illustrated.

In most cases it is desirable to reduce to a minimum the number of welded joints between the pump chamber and other parts of the apparatus. Therefore, it is advantageous for the chamber of the pump to be formed of a special part of a pipe of sufficiently large dimensions which is employed as another part of the apparatus, as exemplified by the embodiments of Figs. 3 and 4. If the dimension of such pipe, having regard to the function of the other part of the apparatus, cannot be chosen sufficiently large, the portion of the pipe to be utilized as the chamber of the pump may be enlarged with the aid of suitable tools.

In certain cases it may be advantageous, in order to insure normal pumping, to separate the chamber of the pump from the solution inlet pipe by providing a constriction in the pipe, like the constriction formed by the conduit 15 in Fig. 1, for example, whereby a certain resistance against back flow of liquid will be created.

Considering the comparatively short longitudinal extent of the pump chamber, difficulties may in certain cases arise in obtaining a sufficient thermal contact-surface with the heat-absorbing element of the apparatus. In such cases this contact-surface may be enlarged by suitably deforming both the flue pipe and pump pipe to increase the heat-conductive relation therebetween.

It has already been mentioned that the operation of the pump is not fully understood. The pump of the invention appears, however, to differ materially from conventional thermosiphon-pumps, on the one hand, which are formed of only a single narrow pipe, and also from so-called bell-pumps, on the other hand. It is possible in each instance to choose such dimensions for the pump chamber that the volume of liquid lifted per unit of time through the pump, by suitable choice of dimension of the heat conductive relation between the pump chamber and the flue, remains essentially constant and independent of the magnitude of the heating effect supplied to the flue when this exceeds a certain

minimum value. Stated another way, by providing an upright pipe having a larger lower part and a narrower upper part and by joining at least the larger lower part to the flue in heat transfer relation therewith on a line substantially parallel to the longitudinal axis of the flue, it is possible to obtain normal lifting of absorption liquid through the pump pipe over a wide range of heat input to the flue.

Thermosiphon-pumps of the type heretofore provided show a very sharply defined maximum value of pumping action since it rises rapidly to a maximum value, and, with continued increase in heat input, drops almost as rapidly. This is especially troublesome, particularly in large apparatus, in that it jeopardizes the normal lifting of absorption liquid by the pump. Under such conditions the pump may be depleted of liquid and produce an operating condition tending to promote corrosion. In the pump of the invention, however, no such sharply defined maximum value of pumping action occurs but the pumping action remains substantially constant and normal lifting of liquid is maintained over a wide range of heat input to the flue and at least up to power values of a magnitude of 400 watts and, in certain cases, up to 500 watts.

I claim:

1. In an absorption refrigeration system, an upright heating tube, a circuit for absorption liquid including a first upright boiler pipe connected to receive liquid at a region removed from the lower end thereof, a second upright pipe and a pump comprising a third upright vapor lift pipe connected to receive liquid in a lower part thereof from the lower end of said first pipe and deliver liquid from a narrower upper part thereof to the upper part of said third pipe, at least one of said first and second pipes and at least the lower part of said third pipe being joined to the exterior surface of said heating tube in heat transfer relation therewith on lines substantially parallel to the longitudinal axis of said heating tube, the lower part of said third pipe allowing free relative movement of vapor and liquid therein and having a larger cross-sectional area than the narrower upper part thereof through which liquid is raised by vapor lift action and heating means for heating at least one of said first and second pipes to expel vapor from absorption liquid therein and for heating said third vapor lift pipe to raise liquid therein only by vapor formed in liquid after it passes into the lower larger part of said third pipe from

said first pipe, said heating means comprising a single source of heat for heating the inner surface of said heating tube in a lengthwise direction of the latter along a zone including the region the lower larger part of said third pipe is in heat transfer relation with said tube.

2. In an absorption refrigeration system, an upright heating flue, a circuit for absorption liquid including a first upright boiler pipe and a pump comprising a second upright pipe arranged to receive liquid in a larger lower portion thereof from a lower part of said boiler pipe and deliver liquid from an upper narrower portion thereof, said boiler pipe and at least the lower larger portion of said second pipe being joined to said heating flue in heat transfer relation therewith on lines substantially parallel to the longitudinal axis of said heating flue, the lower end of said first pipe being bent back upon itself and constituting and serving as the lower larger portion of said second pipe.

3. In an absorption refrigeration system, an upright heating flue, a circuit for absorption liquid including a first upright boiler pipe and a pump comprising a second upright pipe adapted to receive liquid in a lower larger portion thereof and deliver liquid from an upper narrower portion thereof, said boiler pipe and at least the lower larger portion of said second pipe being joined to said heating flue in heat transfer relation therewith on lines substantially parallel to the longitudinal axis of said flue, and a conduit of smaller cross-sectional area than the larger lower portion of said second pipe connecting the latter and a lower part of said first pipe.
